NECKTIE

James Fallar, Forest Hills, N. Y.

Application October 26, 1938, Serial No. 236,977

2 Claims. (Cl. 2—146)

The invention herein disclosed relates to what may be termed a self-drape necktie and comprehend a lining therefor.

By the term self-drape is meant a necktie having a tendency, when knotted, to fold transversely along certain definite longitudinal lines. This tendency is attained in a necktie, as heretofore made, by so constructing the lining therefor, that the completed necktie has certain weaker and stiffer sections longitudinally thereof, and particularly throughout the portion to be knotted. In ties of this type, as heretofore made, the self-draping effect has been attained solely by virtue of varying the strength of the lining along longitudinal lines at the portion of the tie to be knotted.

This has been effected by providing reinforcing strips along the marginal edges of the lining for a short distance and by weakening the lining along certain lines. While such ties have provided a marked tendency to fold transversely when knotted along definite longitudinal lines, this tendency is not as definite and certain as is desirable.

An object of this invention is to provide a self-drape necktie that, as a necktie structure, has a definite and certain tendency, when knotted, to fold transversely along definitely fixed, longitudinal lines. This is accomplished, in accordance with the invention by providing a novel necktie lining and by so arranging the cloth of the necktie that the lining and cloth together form a structure that provides a superior balance of the necessary relative longitudinal stiffness to effect a definite and certain tendency for the necktie, when knotted, to fold transversely along definitely fixed, longitudinal lines.

A necktie so constructed and embodying the invention is illustrated in the accompanying drawing in which:

Fig. 1 is a plan of a lining used in the necktie;

Fig. 2 is a transverse section of a necktie at the part where the knot is formed;

Fig. 3 is a transverse section through the knotted tie just below the knot; and

Fig. 4 is a section similar to Fig. 3.

In the necktie illustrated in the drawing, the tie as it emerges from the knot formed therein has a definite fold along certain longitudinal lines. As shown in Fig. 3 the fold is such as to create one central dimple 1. The edges 2 of the tie are directed rearwardly and two convex portions 3, one on each side of the dimple 1 are directed forwardly. As shown in Fig. 4, the edges 2 of the tie are directed forwardly and a

central convex portion 4 is also directed forwardly. Between each edge 2 and the central convex portion 4, there is a concave portion or dimple 4a. In each instance, the tie, from edge to edge, forms, transversely, a smooth, sinusoidal curve. This drape effect forms definitely and automatically when the tie is knotted.

The self-drape effect is attained in the tie construction illustrated in the drawing by an interrelation of the lining and the arrangement of the cloth about the lining. The lining extends substantially from one end of the necktie to the other and it is a two-ply lining forming a stiff lining for the necktie. One ply 5a varies in width with variations in the width of the tie; its marginal or side edges diverging to fill the lower or widening portion of the tie. The other ply 5b is substantially the same width throughout. This ply of the lining is, however, split longitudinally forming two strips 5c and 5d which are sewn along the margin of the portion of the ply 5a that constitutes the lining in the tie throughout the portion of the tie that is knotted. Both plies of the lining are cut from the cloth on a bias and have some longitudinal elasticity.

The cloth 6 about the lining is arranged to form a central section throughout the portion to be knotted that is stiffer than the side sections. This central section consists of four plies of cloth and one ply of lining. It is formed by carrying the edge 6a past the center line of the tie and by folding over the other edge of the cloth forming layers 6b and 6c. There are therefore in this central section, which is slightly less in width than the distance between the two adjacent edges of the reinforcing marginal lining strips 5c and 5d, layers of cloth 6b, 6c, 6d and the layer 6e. In all other sections there are but two layers of cloth, but adjacent the margins of the tie there are two plies of lining. Thus, the cloth and lining together form a construction that has comparatively stiff marginal and central sections throughout the portion to be knotted and relatively weaker sections between the stiff central section and marginal strip sections.

The arrangement of the cloth and the lining cooperate to form longitudinal sections of different stiffness. These result in a drape effect when the knot is formed in the tie and the tie presents a neat finished appearance on the wearer. For a tie made with a fabric that is of a less pliable nature than the fabrics ordinarily used, the lining may be made to have less resistance to fold in the center by a row of perfora-

tions 5e in the lining along the center and in the portion where the knot is formed.

It is obvious that various changes may be made by those skilled in the art in the details of the embodiment of the invention illustrated in the drawing and described above within the principle and scope of the invention as expressed in the appended claims.

I claim:

- 10 1. A lining for a self-drape necktie having a tendency when knotted to fold transversely along definite, longitudinal lines, which lining comprises two longitudinally elastic plies of fabric, a base ply varying in width with variations in the width of neckties, the marginal side edges thereof of diverging at the end to be knotted, and a reinforcing ply of substantially the same total width throughout and of lesser width than the narrowest portion of the base ply, the reinforcing ply being split longitudinally throughout the portion to be knotted forming two narrow strips of substantially uniform width and of substantially the same width, the two strips diverging and being stitched along the marginal edges of the base ply, whereby the diverging relation of said strips will be
- 15
- 20
- 25

provided in which a self-drape knot can be formed at any one of a plurality of selective points.

2. A self-drape necktie having a tendency when knotted to fold transversely along definite, longitudinal lines comprising in combination a cloth envelope having diverging edges throughout the portion to be knotted and including a reinforced central section formed by several layers of cloth of substantial width and extending 10 equal distances on each side of the center line of the tie, and a lining within the tie comprising two longitudinally elastic plies of fabric, a base ply varying in width with variations in the width of the envelope, the marginal edges thereof diverging to fill the diverging portion of the envelope, and a reinforcing ply of substantially the same total width throughout and of lesser width than the narrowest portion of the base ply, the reinforcing ply being split longitudinally throughout the portion to be knotted forming two narrow strips of substantially uniform width and of substantially the same width, the two strips diverging and being stitched along the marginal edges of the base ply.
